UNITED STATES PATENT OFFICE.

FRANKLIN TOMPKINS, OF NEW DORP, NEW YORK.

ROTARY ENGINE.

931,900.

Specification of Letters Patent. Patented Aug. 24, 1909.

Application filed March 20, 1909. Serial No. 484,609.

To all whom it may concern:

Be it known that I, FRANKLIN TOMPKINS, a citizen of the United States, and residing at New Dorp, Staten Island, in the county of Richmond and State of New York, have invented certain new and useful Improvements in Rotary Pumps and Engines, of which the following is a specification, such as will enable those skilled in the art to 10 which it appertains to make and use the same.

This invention relates to rotary pumps and engines; and the object thereof is to provide an improved device or apparatus of this class adapted to serve either as a pump or engine, 15 and which is simple in construction and operation and may be conveniently managed or manipulated; and with this and other objects in view the invention consists in a device of the class specified constructed as 20 hereinafter described and claimed.

The invention is fully disclosed in the following specification, of which the accompanying drawings form a part, in which the separate parts of my improvement are designated by suitable reference characters in 25 each of the views, and in which:—

Figure 1 is a sectional side elevation of the complete apparatus with part of the construction removed, the section being on the 30 line $x-x$ of Fig. 2, Fig. 2 a view looking in the direction of the arrow x^2 of Fig. 1 and showing the complete apparatus with part of the construction broken away, Fig. 3 a view similar to Fig. 2 but showing only the body 35 of the pump or engine, and showing the cover thereof removed, Fig. 4 an inside view of said cover, Fig. 5 a sectional view of a valve device forming part of my invention, and two of which are employed, the section being 40 on the line 5—5 of Fig. 2, Fig. 6 a sectional side view of a radially movable piston blade, the section being on the line 6—6 of Fig. 3, Fig. 7 a section on the line 7—7 of Fig. 6, Fig. 8 a section on the line 8—8 of Fig. 6, Fig. 9 a section on the line 9—9 of Fig. 6, and;—Fig. 10 a side view of a piston plate 45 packing, two of which are employed in the piston plate shown in Figs. 6 to 9 inclusive.

In the practice of my invention, I provide 50 a casing a which is open at the front and provided with a cover a^2 , and said casing is composed of two approximately circular parts a^3 as shown in Fig. 3 in which are circular chambers a^4 which are placed in communication as shown at a^5 , and the casing a is provided centrally of the top thereof with

a tubular coupling a^6 adapted to serve both as an inlet and outlet under certain conditions, and at the bottom thereof with a similar tubular coupling a^7 adapted to serve 60 both as an inlet and outlet.

Mounted eccentrically in the parts a^3 of the casing a are shafts b which are nearer the center line of the casing a than to the outer side walls thereof, and around these shafts 65 the back and front walls a^2 of the casing a are provided with grooves b^2 which are eccentric to the shafts b but concentric to the centers of the parts a^3 of the casing a .

One of the shafts b is extended at the back 70 of the casing a as shown at b^3 in Fig. 1, and is provided with a drive wheel b^4 by means of which power may be transmitted for any desired purpose. The shafts b are provided with piston heads c which are preferably 75 formed integral therewith and which are provided with radially arranged gear members c^2 in which are mounted radially movable piston blades d . The radially arranged gear members c^2 are slotted radially as 80 shown at c^3 , and these slots extend inwardly into the piston heads c , and the radially movable piston blades d are provided at their inner ends with extensions d^2 adapted to enter corresponding recesses d^3 in the 85 shafts b or in the central parts of the radially movable piston heads c when said heads are formed integral with said shafts.

The radially movable piston blades d are also provided at the ends thereof and at 90 their inner corners with tenons d^3 on which are mounted anti-friction rollers d^4 , and these tenons d^3 with the rollers d^4 are movable in the grooves b^2 in the back wall and front a^2 of the casing a , and in the operation 95 of the pump or engine as hereinafter described, the blades d are moved radially by the tenons d^3 operating in the grooves b^2 .

The blades d are made as shown in Figs. 6 to 9 inclusive, said blades being provided 100 with a central recess or chamber d^5 which opens outwardly and with side grooves d^6 , and the parts d^7 of said blades which separate the recess or chamber d^5 and the grooves d^6 are provided with spring chambers d^8 , and the said parts d^7 are provided in their outer faces with recesses d^9 in the same plane as the recess or chamber d^5 . Placed in the blades d thus formed are two similar packing plates e , one of which is shown in 105 Fig. 10, and these plates consist of a central body portion e^2 adapted to enter the recess

or chamber d^5 and provided at their outer edges with laterally directed members e^3 , and at one side edge one of the members e^3 is provided with an arm e^4 parallel with the body portion e^2 and separated therefrom by a space e^5 , and in the outer part of the body portion of the plate e is an opening e^6 . In practice, two of these plates are placed together as shown in Figs. 6 to 7 inclusive, the 10 arm e^4 of one plate being on one side of the blade, and the arm e^4 of the other plate on the opposite side of the blade, and these packing plates are forced outwardly by means of springs e^7 placed in the spring 15 chambers d^8 and laterally by means of a spring e^8 placed in the recesses or openings e^6 , and the packing plates e are secured in said blades by pins e^9 passed through openings e^{10} in said plates, said openings being 20 large enough to permit of the requisite movement of the packing plates both inwardly and outwardly and laterally, and by means of this construction the outer face of the piston blades d which bear on the outer 25 walls of the chambers a^4 in the casing a are securely packed as are also the radial faces thereof which bear on the back and front walls of said casing.

Connected with the coupling a^6 at the top 30 of the casing a is an elbow coupling f , and a similar elbow coupling g is connected with the bottom coupling a^7 . Connected with the elbow coupling f is a three way valve casing h , and a similar three way valve casing i is connected with the elbow coupling g , and the valve casing i is shown in section in 35 Fig. 5, and the valve casing h which is of the same form as the valve casing i is provided with an exhaust port h^2 , and a steam admission port h^3 on the side of the valve casing h diametrically opposite to the exhaust port h^2 ; and the valve casing i is provided with an exhaust opening or port i^2 and with a 40 steam admission port i^3 located diametrically opposite to the exhaust port i^2 in the valve casing i , and the valve casings h and i are each provided with a valve j having a two way opening j^2 therein, the two ways j^3 and j^4 of which meet at a right angle as 45 plainly shown in the sectional view in Fig. 5, and these two valves j in the two casings h and i are exactly alike and connected together by a valve rod j^5 and adapted to be 50 operated simultaneously by a valve wheel j^6 , and the two valves j are so related with respect to one another that a plan view of 55 one would coincide with the plan view of the other.

As shown in Fig. 1, the ports of the valve casings h and i communicating respectively with the elbow couplings f and g lie in the same vertical plane; and as shown in Fig. 2, the exhaust and steam admission ports h^2 and h^3 of the valve h lie in the same vertical 65 plane with the admission and exhaust ports

i^2 and i^3 of the valve casing i , and the exhaust port h^2 of the valve casing h is directly above the admission port i^3 of the valve i , and the admission port h^3 of the valve casing h is directly above the exhaust port i^2 of the valve casing i . 70

The admission port h^3 of the valve casing h is in communication through the elbows h^4 and h^5 and h^6 and pipes h^2 , k , h^7 and h^8 , and a T-coupling h^9 with a steam supply k , 75 and the steam admission port i^3 of the valve casing i is in communication through an elbow i^4 and pipes i^5 and i^6 and the T-coupling h^9 with the same steam supply k ; and the steam supply k is controlled by a valve k^2 . 80

By turning the valve wheel j^6 , the valves j will take similar positions, the position for the valve in the casing i being shown in Fig. 5, and the flow of steam from the supply pipe k will pass into the valve casing i through the admission port i^3 , through the valve j into the elbow pipe g and into the rotary pump or engine, thus operating the same and passing out through the elbow pipe f into the valve casing h through the other valve j and out 90 through the exhaust port h^2 , and this as will be seen, operates the rotary engine to turn the wheel b^4 in one direction. By again turning the valve j^6 through an angle of 90° , the valve ways j^3 and j^4 of the valve casing i 95 will be brought into communication respectively with the exhaust port i^2 and the elbow pipe g , and the other valve j will be turned through the same angle and the flow of steam will be from the supply k into the admission port h^3 of the valve h through the elbow pipe f and the coupling a^6 into the rotary engine or pump, thus operating the same and passing therefrom through the coupling a^7 and the elbow pipe g into the valve casing i and 100 out at the exhaust port i^2 thereof, and this as will be understood, will reverse the pump or engine. 105

The operation of this apparatus will be similar to that of others of its class, and especially similar to the construction described and claimed in U. S. Letters Patent granted to me on the 2nd day of March, 1909, No. 913,927 except as to the details of the construction described and claimed herein, 115 and the operation thereof which constitute the subject matter of this invention and are set out in the appended claims.

This apparatus may be used for any of the purposes to which such apparatus are usually devoted, and changes therein and modifications thereof may be made, within the scope of the appended claims, without departing from the spirit of my invention or sacrificing its advantages. 120

Having fully described my invention, what I claim as new and desire to secure by Letters Patent, is:—

1. A pump or engine of the class described, comprising a main casing composed of two 130

- cylindrical parts, said parts being provided with circular chambers which are in communication, and said casing being also provided at the top and bottom thereof and 5 centrally thereof with couplings forming inlet and outlet ports, shafts mounted eccentrically in each part of said casing and nearer the communication between said parts than the opposite sides thereof, the 10 back and front of the casing being also provided with circular grooves which are concentric to the centers of said parts of the casing and eccentric to said shafts, said shafts being also provided with piston heads 15 having radial arms, and radially movable piston blades mounted in said arms, said piston blades being provided with members movable in said grooves, three way valve casings connected with the inlet and outlet 20 ports at the top and bottom of the main casing, a main steam supply pipe, branch pipes or couplings connected with the main steam supply pipe and with said valve casings, other pipes or couplings connected with said 25 valve casings and with the top and bottom inlet and outlet ports of the main casing, two way valves mounted in said valve casings, and a single valve operating rod passing through said valve casings and with which 30 said valves are connected.
2. In a rotary pump or engine, a main casing comprising two approximately circular parts having circular chambers which are in communication, said main casing being also provided with top and bottom inlet and outlet ports, three way valve casings connected with said inlet and outlet ports, two way valves mounted in said valve casings, and a single valve operating rod passing through 35 40 said valve casings and adapted to operate said valves.
3. In a rotary pump or engine, a casing, a shaft eccentrically mounted therein, said shaft being provided with a rotary piston 45 head having radial arms, radially movable blades mounted in said arms, the front and back of the casing being provided with circular grooves concentric to said casing, and eccentric to said shaft, and said blades being
- provided with members which are movable in said grooves, said blades being also provided with packing plates or devices which are mounted therein and radially and laterally movable, and springs for forcing said packing plates or devices in both directions. 50 55
4. A pump or engine of the class described, comprising a casing, a shaft eccentrically mounted therein, the front and back of the casing being provided with annular grooves concentric to said casing and eccentric to 60 said shaft, said shaft being also provided with a piston head having radial arms, and radially movable piston blades mounted in said arms and provided with radially and laterally movable spring operated packing 65 devices.
5. In a rotary pump or engine, a main casing comprising two approximately semi-circular parts having circular chambers which are in communication, said main casing being also provided with top and bottom couplings adapted to serve both as inlet and outlet ports, three way valve casings connected with said couplings, valves mounted in said valve casings, and a single valve rod 70 75 passing through said casings and adapted to operate both of said valves, substantially as shown and described.
6. In a pump or engine, the combination with a casing composed of two cylindrical parts and having concentric grooves, of a head with corresponding grooves, inlet and outlet pipes at the meeting point of the two cylindrical parts, eccentrically located shafts, slotted intermeshing wheels on the shafts, 80 85 pistons working in the slots of the wheels and valves with a common stem working in the inlet and outlet pipes to reverse the flow of the fluid.

In testimony that I claim the foregoing 90 as my invention I have signed my name in presence of the subscribing witnesses this 19th day of March 1909.

FRANKLIN TOMPKINS.
